RECORD CHANGER

Willard J. Faulkner, Chicago, Ill., assignor to
 Advance Engineering Company, Chicago, Ill., a
 partnership comprising K. D. Turner, John
 Huarisa, L. C. Parks, and J. H. Clippinger

Application May 17, 1941, Serial No. 393,984

11 Claims. (Cl. 274—10)

This invention relates to improvements in automatic record changing mechanisms, and more particularly to a type of record changer wherein the records are played on one side only, being stacked above the turntable and supported in that position by a support substantially in the center of the record and by at least one other supporting point on the periphery thereof. It applies particularly to a type of mechanism in which records are dropped one at a time into playing position on a turntable by moving the lowermost stacked record laterally, the released record being guided to the center of the turntable by a record guiding spindle.

The movement of the record is very similar to that shown in the copending record changer patent application of Arnold W. Leline, Serial No. 375,179, filed January 21, 1941. The center spindle is similar and operates in substantially the same manner as the device shown by said Leline application, and also as shown in the copending application of Willard J. Faulkner, Serial No. 380,248, filed February 24, 1941.

Although record changers of the described type are well known, there have been many disadvantages incorporated therein which it is the purpose of this invention to overcome. In general, these changers have been quite complicated, require a considerable number of die-cast pieces, and require a large volume of space to contain them. In view of the difficulty of obtaining die-cast metals during world crises, the space requirements and complexity of the prior record changing mechanisms, a new, more simple, method of construction and operation has been devised.

Among the various disadvantages of the prior art record changing mechanisms has been the stop or trigger mechanism which initiated the record changing mechanism. Very often these prior mechanisms were ineffective in operating the release mechanism due to the particular design of stopping or lead-out groove which caused the device to automatically go through the record changing cycle. This necessitated the manual playing of these types or makes of records.

It is, therefore, an object of this invention to provide an improved record changer which is simple to construct, light in weight, and does not require a great volume of space for housing the same.

Another object of this invention is to provide a record changer which has a minimum number of moving parts, operable either during the record playing or record changing cycles.

Another object of this invention is to provide a record changing mechanism which, for the most part, can be constructed of materials which can be shaped or formed in a punch press and which requires no die-cast pieces.

5 Another object of this invention is to provide a record changer mechanism wherein the time consumed for changing the records between playing cycles is greatly reduced.

10 Another object of this invention is to provide a record changer mechanism which is rugged, has a minimum number of adjustments and is not easily thrown out of adjustment.

Another object of this invention is to provide a record changer which may be quickly, easily and simply adjusted to play records of different sizes.

20 Still another object of this invention is to provide a record changing mechanism which will operate automatically with any type of lead-out or stopping groove on the record.

25 These and other objects of invention including those of ease in manufacture, economy in construction, simplicity in adjustment, as well as the invention itself, will become more apparent from the following description, which is illustrated by the accompanying drawings.

In the drawings:

30 Fig. 1 is a top plan view of an embodiment of the record changing mechanism constituting the invention, some parts being broken away to show more clearly certain other parts below, certain otherwise hidden parts being indicated by dotted lines;

35 Fig. 2 is a vertical section of the record changing mechanism shown in Fig. 1 taken along the line 2—2 thereof, certain parts being shown in elevation, and others omitted;

40 Fig. 3 is an elevational view of the removable center spindle;

45 Fig. 4 is an elevational view of the removable center spindle shown in Fig. 3, but rotated through 90° in a counterclockwise direction;

Fig. 5 is a vertical sectional view of the center bearing taken along the line 5—5 of Fig. 1;

Fig. 6 is a bottom view of the bottom bearing and spindle support bracket taken from a plane indicated by the line 6—6 of Fig. 5;

50 Fig. 7 is a vertical sectional view of the side record support post taken along section 7—7 of Fig. 1;

Fig. 8 is a horizontal sectional view of the side record support taken along line 8—8 of Fig. 2;

Fig. 9 is a fragmentary vertical section of the side support taken along line 9—9 of Fig. 1;

Fig. 10 is a fragmentary sectional view of the pickup arm assembly taken along the line 10-10 of Fig. 1, the arm, however, being rotated so that it falls along the plane through the center post;

Figs. 11 and 12 are a top plan and side elevational views respectively of the ejector slide;

Fig. 13 is a top plan view of the record changing mechanism below the turntable level with the frame and motor removed. In this view the mechanism is shown set for playing ten-inch records as it would be positioned at the start of the record playing cycle;

Fig. 14 is a top plan view similar to Fig. 13, but set for playing twelve-inch records;

Fig. 15 is a top plan view similar to Fig. 13 except the mechanism is shown at the moment the trip mechanism starts the changing cycle;

Fig. 16 is a top plan view similar to Fig. 13 except the mechanism is shown at the moment after the record change has occurred and the pickup control mechanism is not yet in position to place the pickup on the edge of the record;

Fig. 17 is an enlarged vertical section taken along the lines 17-17 of Fig. 1;

Figs. 18 and 19 are bottom plan views of the pickup control levers showing the different relative positions taken therein and with a portion of the slide bar shown in dot-dash lines in Fig. 18;

Fig. 20 is a fragmentary bottom plan view of the end of the slide bar showing the brake used to restrict the movement of the levers of Figs. 18 and 19;

Fig. 21 is a perspective view of a part of the linkage used to trip the record changing mechanism; and

Fig. 22 is a fragmentary plan view of a portion of the velocity trip mechanism showing a modified form.

In the drawings, like parts have been designated with like reference characters.

Briefly, the invention includes a supporting frame or bed upon which the entire mechanism is mounted, a turntable is provided for rotating the records and may be rim driven; the record changing is effected by an eccentrically mounted wheel, normally held out of engagement with a friction drive wheel fastened to the turntable shaft which rotates upon engagement therewith for effecting the record changing operations; the eccentric wheel is carried by a slide member and causes the slide member to move when the eccentric wheel is engaged with the friction wheel. The slide member is mechanically linked to the various parts of the changer to cause the pickup arm to be lifted off of the record and swung laterally to one side, after which a new record is released. The pickup arm is then returned and lowered to its proper point on the edge of the record. Trip means is provided linked with the pickup arm to cause the eccentric friction wheel to engage with the spindle wheel. Means is provided in the form of a mechanical linkage which may be manually controlled for the playing of either twelve or ten inch records, said means definitely determining the return position of the pickup arm so that it is properly positioned for playing either ten inch or twelve inch records. Means is also provided for quickly removing the played records from the turntable.

More specifically, as best shown in Fig. 2, the apparatus comprises a generally rectangular mounting plate or bed frame 20 formed of pressed metal and having its edge terminating in a downwardly extending peripheral flange 21; the

intermediate portion is formed with a downwardly pressed turntable recess 22 in which the turntable is partially disposed. Upwardly extending pickup arm and record support posts 23 and 24 are integrally welded to the base plate. The frame 20 forms the base or mounting plate for the entire record changing mechanism, thereby holding together the various components to form one integral assembly unit. This frame may be mounted in a suitable cabinet.

A turntable 25 is provided and is seated on a hollow spindle 26 which is in turn rotatably journaled in a top bearing 27, Fig. 5, mounted on the frame 20 and a bottom bearing 28 supported in a sub-frame 29. The sub-frame (Fig. 6) comprises a generally rectangularly formed steel member 29 secured to the main frame 20 by means of three screws 30. In order to insure precise alignment of the bearings 27 and 28, two half punches 31 are provided in the sub-frame which engage in two holes or recesses in the main frame. (See Figs. 5 and 6.) For holding the spindle against thrust movement and to reduce the friction caused by the weight of the records upon the turntable, a thrust bearing 32 is provided which rests on the top bearing 27 surrounding the hollow spindle 26. The turntable has a hub 33 which is telescoped over the protruding end of the hollow spindle and rests upon the top face of the thrust bearing. A washer 34 is disposed between the turntable hub and the top race of the thrust bearing for absorbing vibrations of the ballbearings and the surface of the raceway in the thrust bearing 32. This washer may be made of cork or other resilient material. A similar resilient washer is positioned below the lower thrust bearing raceway and the bearing 27. A metallic washer 182 is disposed between the cork washer 34 and the turntable hub 33; this washer carries the trip lug 183, hereinafter more fully described. The turntable is securely fastened to the hollow spindle by means of the conical nut 35 which is threaded on the hollow spindle 26 and holds the turntable hub and washer 182 against the shoulder on the spindle 26. The lower end of the sub-frame 29 has secured to its a bracket 37 which contains a D shaped hole 38 for receiving the record spindle (Fig. 6). To insure correct coaxial alignment of the D hole 38 with the opening through the hollow spindle 26, the two clearance holes in the bracket 37 through which the screws 40 extend are made sufficiently large to allow the adjustment of the bracket before they are tightened to hold the bracket in position.

The D shaped hole 38 is designed to receive the semi-cylindrical end 41 of the record spindle 42 and holds the same against rotation but allows it to be easily removed and replaced in the same relative position.

The record holding spindle 42, as best shown in Figs. 3 and 4, includes a lower straight cylindrical body portion 43 adapted to be slidably disposed in the bore of the hollow turntable spindle 26 and terminating in an end 41 adapted for locking engagement in the D shaped hole 38. The cylindrical portion extends upward slightly beyond the top of the hollow spindle where it is provided with an enlarged record guiding body portion 47 of substantially the same diameter as the end of the spindle 26. A shoulder 48 is provided adjacent the part 41 for engagement with the bottom bracket 37 and to hold the shoulder 44 formed at the junction of the body 47 with the part 43, out of engagement with the end of

the hollow spindle 26. The body 47 is of gradually reduced diameter at 48, terminating in a flat record supporting head 49 of substantially the same diameter, and which is slightly smaller than the center hole of the standard records.

The portion 47 extends above the spindle 26 for a distance which is determined by the thickness of the stack of records to be played, additional room being allowed between the bottom of the stack of unplayed records, which rest on the head 49, and the last played record, which rests on the turntable, or above the turntable on the records that are guided by the body 47.

The spindle 42 terminates in an extension 50 of rectangular cross section for holding the stacked records which extends in prolongation of the spindle body, but is offset therefrom. In this respect the record-holding spindle differentiates from the structure of the aforementioned Faulkner application. The body is connected to the head 50 by a neck 51 which is of a length equal in thickness to the thickest commercial ten inch or twelve inch record. The edge 52 of the neck 51 lies in the same plane with the edge of the head 50, while the edge 53 is a plane in prolongation of the spindle body 47.

The head 50 of the spindle is provided with a means for holding the bottom-most record on the flat head 49 and with the edge of the record hole in engagement with the edge 52 of the neck 51 in order to prevent accidental and premature discharge of the bottom-most record of the stack. This is accomplished by providing a U-shaped spring 56, the bight of which extends through a hole 54 in the upper end of the head portion 50 of the spindle 42. The ends of the spring 56 extend downwardly on both sides of the head following the contour of the surface 55 in spaced parallel relation to the neck surface 53 and terminates below the level of the upwardly facing head 49. It is held in place by means of the clip 57 which is riveted or welded to the head. The spring may be pressed inwardly toward the neck portion 53 by the inside edge of the record to permit the record to slide laterally on the head 49 of the spindle until the hole in the record is coaxial with the periphery of the head 49 after which it drops down toward the turntable.

The spring 56 is of sufficient resiliency so that it may be easily bent when the lowermost record is displaced, but still of sufficient stiffness to prevent accidental displacement thereof.

In operation, the centers of the stack of records are engaged at the periphery of the center hole by the head 50 while the lowermost stacked record rests upon the upwardly facing shoulder 49 but may be slipped laterally to the right, as viewed in Fig. 2, against the resiliency of the spring 56 and against the edge of the neck 53, after which it may fall over the shoulder and slide down the spindle 42 toward the turntable. The zone 48 of the spindle is of a reduced diameter which prevents the record from being wedged on the spindle when tilted. The weight of the stack of unplayed records on the head 49 is transmitted through the spindle 42 to the frame 37, thus preventing friction of the stationary record holding spindle with the rotating turntable spindle.

The turntable 25 may be driven in any suitable manner such as by a geared drive or belt drive connection to the hollow spindle 26 or the turntable 25. One preferred form, both from the standpoint of smoothness of drive and economy, is provided by a motor 58 (shown in dotted out- 70 75

line in Fig. 1) which has a drive wheel 59 in frictional contact with a rubber rimmed wheel 60 which in turn is in frictional driving contact with the inside of the downwardly extending rim flange 61 of the turntable 25.

The rubber rimmed wheel 60 is held in slight frictional contact with the wheel 59 and the rim flange 61 by means of a light spring, not shown. The wheel 60 is placed in such a position with 10 relation to the motor wheel 59 and the flange 61, that it is pinched therebetween when the motor is powered to drive the system; thereby gaining 15 good driving contact. By this method of mounting, flattened portions are prevented from being formed on the surface of the rubber rim by the drive wheel when the system is not in operation inasmuch as the force necessary for good driving friction is present only when the motor is turned on and the rubber rimmed wheel disengages itself when the motor power is removed.

The driving of the record changing mechanism is accomplished by an annular rubber ring 62 disposed on the hollow spindle 26 between the top bearing 27 and the bottom bearing 28. This 20 ring is adapted to contact with the upwardly formed flange 64 of the eccentrically mounted wheel 63 (see Figs. 1 and 17).

The eccentric wheel is mounted on a slide bar 69 and is adapted on rotation to reciprocate the 30 slide bar which is slidably supported by the frame 20. The reciprocation of the slide bar causes the operation of the record changing mechanism.

The wheel 63 is provided with an eccentrically 35 disposed hub 65 (Figs. 2 and 17) which is provided with two set screws 66 adapted to tighten the bushing on a shaft 67. The shaft 67 extends upwardly through a bearing 68 staked into a slide bar 69 at 68', and carries on its end a cam member 70. Thus the eccentric wheel 63 and cam member are rotatable together and the cam may be moved to start the rotation of the eccentric wheel.

The eccentric wheel is so mounted that it is 40 normally out of driving relation with the drive ring 62 (Fig. 17), and when rotation of the wheel is started, by movement of the cam 70, it engages with the drive ring 62, which rotation continues for substantially one complete revolution. In carrying out this function the slide bar 69 is 45 provided with an opening 71 of size sufficient to allow the hollow shaft 26, with the elements mounted thereon, to extend therethrough. It also contains two longitudinally extending slots, 50 one 72 in the eccentric wheel end, and the other 73 in the opposite end. The slide bar is secured to the main frame by means of two shoulder screws 75 threaded into two spacers 75' which extend through the slots 72 and 73 (Fig. 17). The 55 position and length of the slot 72 in the slide bar is determined to limit the travel of the bar, and it is normally held in such a position that when the eccentric wheel is positioned with its shortest radius toward the ring 62, it is just out of engagement with the rubber drive ring 62, which position is shown in Figs. 1, 13, 14, and 17. A coil spring 77 holds the slide bar in that position, i. e., in a position which the end 78 of the slot 72 is held in contact with the shoulder portion of the screw 75. This is accomplished by stretching the spring 77 between the hole 80 on the slide bar 69 and the hole 81 on the main frame 20, the relative position of which is indicated by the dotted circle 81 on the drawings.

To be sure that the eccentric wheel 63 is held

in an indexed position out of engagement with the ring 62 during the record playing cycle, the cam 70 is provided with a flattened portion 82 (Figs. 15, 16, and 17) which is engaged by a spring 82a which resiliently holds the wheel against rotation. One end of this spring is fastened against the side portion of the slide 69 by means of the rivet 83. An alternative assembly makes the cam member 70 an integral part of the eccentric wheel 63; or still another fastens the spring on the eccentric wheel and provides detents upon the slide bar for engaging the spring.

A means to be described later is provided for moving the cam 70 to urge the eccentric wheel out of its indexed position in the direction indicated by the arrow 84 (Figs. 13, 16), to cause the periphery 64 of the eccentric wheel 63 to engage the ring 62 on the hollow spindle 26. The wheel 63 is thereupon rotated by frictional engagement with said ring and, since it is eccentric, the slide bar member 69 is reciprocated longitudinally by the action of the eccentric wheel against the hollow spindle drive ring.

The eccentric wheel moves the slide and the slide is arranged to move the pickup over through its cycle, as well as to cause the changing of a record. The slide is of channel shape and is provided with a cam bracket on its inside upper surface which cam comprises a low flat portion 87 on the slide which inclines upwardly at 88 and terminates in a higher flat portion 89.

The pickup arm 99 may be of the conventional type having a pickup cartridge, not shown, secured into its unsupported end. A record groove-engaging stylus is secured into the cartridge and the usual connections are made to the cartridge for the purpose of conducting electrical impulses into the amplifying apparatus. A bracket 105 is mounted on the end of the pickup arm by means of vibration-absorbing grommets 106, and is secured in place by means of two screws 107 which extend through the grommets and thread into the arm. The bracket is provided with two downwardly extending parallel flanges or sides 108 having aligned holes therein to accommodate a hinge pin 109 therethrough. A smaller bracket 110 is also hingedly secured on the hinge pin 109. The bracket 110 has a bushing 110' by means of which it is adjustably secured to the top of a sleeve 102 by means of a setscrew 111 extending through the bushing and engaging the sleeve 102. Means is provided for relieving the pressure, due to the weight of the pickup and arm, on the record, and constitutes a spring 100 connected to a downwardly extending tab 100' on the bracket 105 and the part 110. Means for controlling the elevation of the pickup arm is provided by an adjustable screw 112 which screw is threaded into the arm and held in adjusted position by the locking spring 112'. The pickup arm is raised by the shaft 86 which is slidably disposed in, and extends through, the sleeve 102, the bottom end of which engages the cam 88 on the slide bar 69, and the upper end of which engages the screw 112.

Upon reciprocation of the slide bar 69 in the direction of the arrow 85, the pickup raising pin or shaft 86 being normally at rest on the lower flat portion 87 of the cam bracket is forced upward by contact with the inclined portion 88 until it comes to rest on the top horizontal portion 89 of the cam bracket. (Fig. 10.)

After the slide 69 lifts the pickup arm in the

manner described, continued movement of the slide causes the arm to be swung. The swinging movement of the pickup arm is effected by the slide which contacts the lever mechanism 92 and 113 on the bottom of the sleeve 102. These levers are so arranged that the slide causes the arm to be swung well beyond the edges of the records, after which a record is dropped and then the arm is returned to playing position on the dropped record. Rotation is accomplished through the lower end of the sleeve 102 which carries a bushing 97 to which is secured a lever 92. The lever mechanism comprising the levers 92 and 113 are connected to the sleeve 102, as described, the lever 92 rigidly, and the lever 113 rotatably journaled on the bushing and connected to the lever 92 by means of the spring 114 (see Figs. 18 and 19). This spring holds a lug 117 on the lever 92 against the edge 118 of the lever 113 (Fig. 18). Movement of the lever mechanism is effected by the slide 69, the lug 91 of which contacts a lug 92' on the lever 92. The motion of the lever mechanism, and the lever 92, in swinging the arm outward, is positive. The lever 113 may be restrained or stopped in its rotation with the lever 92 because of the spring connection between the two. This, as will later be seen, is effective to index the return position of the pickup arm. Here it should be noted that because of the manner in which the pickup arm moves, the lever, i. e., lug 91, engaging 92', that this move is positive only in one direction, and that when the slide returns the pickup arm lever mechanism is not positively returned by the slide. This return movement is effected by the spring connection between the levers 113 and 92. That is, when the slide starts to move the levers they move together until the edge 118 of the lever 113 strikes a pin or lug 119 on the record size bar 120. The lever 113 then stops, and the slide 69 continues the movement of the part 92, causing the relative movement between the now stopped lever 113 and the lever 92, the spring 114 stretching and allowing such movement; the position then taken by the parts is best shown in Figs. 16 and 19. When the slide 69 returns, being pulled back by the spring 77, the lever 92 is pulled back by the spring 114 until the lug 117 on the lever 92 engages the edge 118 of the lever 113. Further backward movement of the lever is restricted by friction between the bearing surfaces which is sufficient to prevent further movement of the pickup arm toward the center of the record. In event this friction shall be found to be insufficient a suitable brake may be supplied, connected to the slide bar and effective only during the time the arm is being swung. This constitutes a brake lever 115 (Fig. 20) slidably secured to the bottom of the slide bar 69 by means of screws extending through a longitudinally extending slot to permit relative longitudinal movement thereon and held by a spring 115a.

It will be seen that the brake may be moved longitudinally outward of the bar. A brakeshoe 116 extends upward and is adapted to engage the levers 92 and 113, as best indicated in Figs. 16 and 18, at the circular portions 92a which may be considered as the hubs of these levers. It will also be seen that it may be desirable to have the hub portion of one of the levers smaller than the other in order that the brake engage only one of them. Also the brake may be arranged to restrict movement of the lever 113 at some other point, the idea being to have the brake applied only

during the swinging of the lever and pickup arm, and to release the same during the playing of the record to allow the pickup arm to swing fully.

When the pickup arm is swung free of the record, the slide continues its movement and causes a new record to be ejected from the stack. This is accomplished by a lug 93 on the slide 69 which engages the downwardly extending end portion 94 of a lever 95 pivotally supported on the underside of the frame 20 at 161, rotating the lever about its pivot. The other end of the lever 95 is connected to the shaft 141 of the ejector mechanism.

The ejector head and side support mechanism 133 is supported on top of the rectangular base plate 132 and includes an ejector slide 134 slidably disposed thereon. The body of the ejector slide is of generally rectangular formation (see Figs. 11 and 12) and has a pair of arms at the opposite ends thereof, each of which extends laterally at 135 and vertically at 136. The outer edges of the upwardly extending portion inclined downwardly at 137, the purpose being to prevent the ejecting arms from slipping off the edge of the record.

Along the center line of the ejector slide and at one end is formed a square opening 138, the edges normal to the axis having upstanding flanges 139 (Fig. 11). The flanges are disposed for engaging with the edge of a cam 140 which comprises a circular disc eccentrically carried on the shaft 141 which in turn is rotatably disposed in the sleeve 131 (Fig. 8). Rotation of the cam 140 by means of the shaft 141 reciprocates the ejector 134 on the rectangular plate.

The body of the ejector slide 134 is narrower crosswise than the base plate 132 and is held and guided on the platform by the head 142 which head not only supports the edge of the stack of records, but encloses the ejector mechanism on top of the rectangular plate.

The head comprises a substantially rectangular hollow body (Fig. 7) having downwardly extending lugs or bosses 143 which engage the plate 132 (Figs. 8 and 9) and extending between the arms 136 of the ejector. The inner sides of the lugs form a guide for the ejector slide 134. A downwardly extending flange 144 extends around the remainder of the head connecting the mid-section to the bosses 143 which extend below the flange a distance slightly greater than the thickness of the ejector slide. The head is secured to the rectangular base plate by means of screws 145 which extend through the bottom of the rectangular platform into the threaded openings in said bosses.

The head thus holds and guides the ejector on the rectangular mounting plate and allows the ejector slide to be easily reciprocated by the cam 140. The vertical arms 136 of the ejector slide extend up beside the edges of the head and slightly above the upper surfaces thereof (Fig. 7), the extension above the head being slightly less than the thickness of a standard ten inch record. The edge of the stack of records rests upon the portion of the head which extends toward the turntable (Fig. 2). The arms 136 of the ejector slide being in a position to engage the edge of the bottom-most record and still miss the record juxtaposed above.

Means is provided for steadyng the stack of records and securely holding them against the platform and comprises a hollow boss 146 on the top of the head 142, which pivotally carries the

yoke 147 having the end 148 which rests against the uppermost stored record. The yoke extends through the boss and is provided with a crank portion 149 to which is secured one end of a spring 150, the other end being secured to a pin 151 disposed below the boss.

The head 142 is symmetrical to a plane passed through the center boss portion positioned at right angles to the line of motion of the slide, making two identical halves. It is eccentrically positioned with respect to the sleeve 131 and is indexed into either of two positions one hundred and eighty degrees apart. The indexing means comprises a pin 152 in the rectangular base plate 132 and two holes 153 in the side support post 24, for the accommodation of said pin. The head may be rotated into the proper position for playing ten inch records as shown in Fig. 1 which position places in the direction of the center post the portion of the head having the greatest length from the center of rotation, or it may be rotated to the opposite position, which position is used for playing twelve inch records. This is accomplished by grasping the head and lifting it so as to disengage the pin from one of the holes and rotating it until the pin is coaxial with the opposite hole at which time the head is released. When the head is rotated the cam 140 is likewise rotated and being in engagement with the upturned portion 126 on bar 120 determines the position of the bar.

The cam 140 in the ejector head is rotated by the shaft 141, as previously stated, the lower end of which has a lever 155 fastened thereto by means of a setscrew 156. The unsupported end of lever 155 has a stud 157 swaged into it. Over this stud the hole in one end of the link 158 is slipped. The opposite end of the said link 158 slips over a similar stud 159 in lever 95 and the two studs are drawn toward each other by means of a spring which spring serves to hold the link in place and to prevent its rattling. Thus by means of lever 95 (whose motion is determined by the slide 69) rotating around pivot 161 fastened into the base 20 through the link 158, lever 155, shaft 129, and cam 140, the record ejector slide is reciprocated during the record changing cycle.

Continued rotation of the eccentric wheel 63 brings it to a point where the maximum radius lies between the hollow spindle shaft 26 and the shaft 67 of the eccentric wheel, which position is shown in Fig. 16. At this point the reciprocation of the slide bar 69 ceases in the direction of the arrow 85 and starts through the action of spring 77 into motion in the opposite direction. Continued motion of the slide bar in this new direction causes the lug 98 to engage the portion 94 of lever 95, which movement is communicated to the ejector 134, the arms 136 of which are now under the records of the stack, to cause the ejector slide to be retracted and allow the next record to drop down where it is ready for engagement with the ejector. During the return movement of the slide 69 the lug 91 on the near end of the slide allows lever 92 to return against the action of the spring 114 to the point where tab 117 of lever 92 engages portion 118 of lever 113. This causes the pickup lever to return to playing position over the outside record groove. After this has occurred the pickup raising pin 86 is lowered through its sliding action against the incline 88 to its rest position on the portion 87 of the inclined bracket. At the same time, the eccentric wheel is rotated until it disengages

from the ring 62 and then through the action of the indexing spring 82a, the wheel pulls away from the drive wheel and is indexed in a non-engaging rest position.

The record size lever 113 contains one surface 118 shown in Fig. 12 engaging head 119 of size selecting bar 120. When the bar 120 is in position as shown in Fig. 13, levers 113 and 92 can be rotated until the point 121 on 113 contacts head 119 on lever 120 which position is adapted for playing ten inch records.

The record size selecting bar 120 is adapted to slide on the bed and is fastened thereto by means of shoulder rivets 123 which extend through the two slotted holes 122 in the bar and are fastened to the bed 20. This bar is held against a cam by means of spring 125 secured to the bar 120 and to the base frame 20, but may be moved in the opposite direction against the force of the spring by means of a cam 128.

The cam 128 (Fig. 7) is fastened to a sleeve 131 which extends upwardly through the hole 129 in the base frame 20 and through a hole 130 in the support 24, and is secured to the rectangular base plate 132 of the ejector head, which rests on top of the support.

The mechanism which starts the eccentric wheel 63 and causes it to engage with the ring 62 on the hollow spindle is sometimes referred to as a differential or velocity stop mechanism. It is adapted to be set into operation by means of the pick-up arm 69.

During the record playing, part of the cycle, lever 113 is rotated clockwise as viewed in Figs. 13 and 16 through the action of the pickup arm following the record groove. This motion is communicated to the sleeve 102 through the bracket grommets 106, hinge members 105, 108 and 119, and the contact of the upstanding ear 117 on lever 92 with the member 113. The rotation of lever 113 is communicated to link 164, the link 164 being connected by stud 163 to lever 113, to pull the link causing a stud 165 at the opposite end of the link to be moved (see Fig. 21). Stud 165 slides in a slot 166 in a sector 167 until the stud contacts the end of the slot. At this point, continued rotation of lever 113 causes the link 164 to pull the sector 167 which revolves around its supporting shaft 169, which shaft supports sector 167 and a lever 170 and is fastened into the base 20. The lever 170 is also caused to be revolved with sector 167 through the action of a friction spring 168 adjustably carried by the lever 170 and which engages with the upper surface of said sector. The lever 170 pivotally supports on its end a member 172 (Figs. 15 and 16) which is held at right angles to lever 170 by a spring 202, a lug 203 being provided on the lever 170 for engaging the side of the lever and resisting its movement. The member 172 carries on one end a cylindrical rubber bumper 172' and on the other end a downwardly extending lug 179. Swinging of the lever 170 urges rubber bumper 172' in a direction toward the turntable spindle and the lug 183 rotating therewith. If the inward motion of the rubber bumper is small, lug 183 strikes the bumper 172' substantially tangent thereto such that the vector forces are substantially longitudinal of the member 172, and moves it, together with the lever 170, away from the spindle of the turntable. The lever may move relative to the sector because of the friction spring connection therebetween. When the motion of the lever 170 is sufficient to cause the rubber bumper 172' to be moved well into the path

of the lug 183, it is struck by the lug 183 at such a point, approximately the diameter of the bumper 172', that the force is transversely applied to the lever 172, which causes the lug 183 to rotate the lever 172 away from the tab stop 203 on the lever 170 around the pivot 177 and against the action of the spring 202 fastened to the levers 170 and 172 (see Fig. 15).

Rotation of the lever 172 around the shaft 177 brings downwardly formed tab 178 against upwardly extending lug 180 on cam 70. By this motion the lug 180 causes the eccentric wheel to move, whereupon it engages with the ring 62 which continues the rotation of the eccentric wheel for one complete revolution to cause the device to go through its change cycle. A pin 181 secured to the bar 20 limits the movement of the arm 170 away from the turntable spindle.

A modified form of this eccentric wheel starting mechanism is illustrated in Fig. 22. Its operation is quite similar to that described. In this instance, however, the cam 270 is connected to the eccentric wheel and is provided with an outwardly extending abutment 270 which is adapted to engage with the lug 272 on the dog 273. The dog 273 is pivotally supported at 274 on the slide and held in spring-pressed engagement by a spring 275 against the cam. A spring 276 connects to a pin 277 on the cam and at 278 on the slide, urging the cam and wheel in a counter-clockwise direction.

In operation the lug 183 on the turntable spindle rotates into contact with the bumper 172' on the lever 172. The lug 179 on the lever 172 hits the upstanding lug 279 on the end of the dog 273 moving the dog and lug 272 out of engagement with the lug 271 on the cam. The spring then rotates the cam and the eccentric wheel into engagement with the drive ring on the spindle. The eccentric wheel moves through its cycle and is finally stopped by the engagement of the lug 271 on the cam with the lug 272 on the dog, the spring 276 then holding the cam in position with the eccentric wheel out of driving engagement with the spindle until the next cycle starts.

As best shown in Figs. 13 and 14, the record size bar is adjustable to two positions by the cam 128 and each of these positions determines the return position of the pickup arm playing either ten inch or twelve inch records. In the position shown in Fig. 13, when the pickup arm is swung outward by means of the slide 69 engaging the lever 92, which is connected to the lever 113 by the spring 114, the lever 113 is restrained in its movement by the edge 118 contacting with the lug 119 on the record size bar. This stops the lever 113 but allows the slide bar to continue the movement of the lever 92, as best shown in Figs. 16, 18 and 19, to allow the pickup arm to be swung well beyond the edge of the turntable and any record that may be thereon, after which the record from the stack is dropped. When the slide bar 69 is returned by the spring 111 the lever 92 is rotated by the spring 114, the lever being held by contact with the lug 119 on the bar 120 until the lug 117 contacts the edge of the lever 113. Inasmuch as the slide bar movement is positive in only one direction, the slide bar may return to its normal position, leaving these levers 113 and 114 in the position shown in Fig. 13. The frictional means for preventing the levers from moving easily during the movement thereof by the slide bar has been previously described. It should be noted that after the pickup arm has

been lowered onto the record, the brake means 116 is removed from contact with the levers 92 and 113, and they are now free to swing, being only held by the pickup arm.

In the position shown in Fig. 13, as previously shown, the pickup arm is in position to be lowered onto a ten inch record. If the slide bar is moved to the position shown in Fig. 14, the cam 128 being rotated substantially 180°, then the lug 119 is positioned opposite the step 121 on the lever 113, which allows the lever 113 to be moved several degrees further than is shown in Fig. 13, which distance represents the larger radius of the twelve inch record. The movement of the pickup arm beyond the edge of the turntable is otherwise the same, the only difference being that the lever 113 is now indexed so that when the pickup arm is returned toward the turntable through the agency of the lever 92 and spring 114, it is in a position to be dropped into the start of the record grooves of the twelve inch record.

A switch means and a rejecting means are combined in a single knob 185 located on the corner of the frame 20. The knob is fastened to the switch 187 through the shaft 186. To this shaft is also fastened the lever member 188 which through the connecting pin 189 is connected to reject rod 190 (see Fig. 1 and Fig. 13). Rotation of the shaft 186 in a counterclockwise direction moves the end of rod 190 against the upstanding end 191 of lever 113 and rotates it clockwise. This action is communicated through the link 164, as just described, and causes the changer to go through the record changing cycle.

Having described the action of the individual components of the automatic record changer which forms one embodiment of this invention, the following summary of operation has been written to tie together their operation.

In playing the record changer, the spindle 42 is dropped into the bore of the hollow spindle shaft 26 and the lower or flattened portion 41 thereof is engaged with D hole 38 in the bracket 37 preventing rotation thereon. The record side support head 142 is rotated to conform to the size of records being played; a group of records are then slipped over the end of spindle 50 and the lowermost record brought to rest at the center on the upward facing shoulder or head 49 and on the side support. The motor is turned on and either the pickup arm 99 is moved toward the center post and released, or the reject knob is turned to the reject position. This initiates the eccentric wheel which operates the changing mechanism and causes the lowermost stacked record to be dropped onto the turntable and the pickup arm with the record groove following stylus to be lowered onto the edge of the record. The stylus follows the groove in the record rotating the pickup arm around the pickup support post 23 and hence the hollow sleeve 102. The hollow sleeve being joined to the lever member 92 causes it to rotate moving with it lever member 113. This motion of lever 113 is communicated to the sector 167 and thence to the lever 170. During the first period of playing, the rotation of lever 113 is insufficient to cause the sector 167 to rotate since the stud 165 merely slides in the slot 166. After this portion of the record has been played, stud member 165 contacts the ends 168 of the slot 166 causing sector 167 to be rotated. Through the action of the friction spring 168, operating on the top of the sector, the lever member 170 is rotated in the same direction.

While the record is being played the distance traveled by the lever arm 170 is just sufficient to cause the lug 183 rotating around the turntable spindle to strike the end of the rubber bumper 172' moving back the lever 170 against the friction of the spring 168. When, however, the record groove following stylus engages the carry out grooves near the center of the record, i. e., grooves which are of greater pitch than the playing grooves or are eccentrically placed, the rubber bumper 172' is struck on its side by the lug 183. This striking action causes lever 172 to rotate away from its stop tab 203 around the bearing 177 against the action of the spring 202, causing the downwardly formed portion 179 thereof, to strike the lug 180 on the cam 70, rotating the cam and the eccentric wheel 63 out of its indexed position and causing the wheel to engage with the rubber friction ring 62 on hollow spindle 26. Rotation of the eccentrically mounted wheel is continued so long as ring 62 and the wheel are in contact. Continued rotation of this wheel causes the slide bar 69 to be moved to allow the increasing diameter of the eccentric to pass between the two shafts. As the slide bar 69 is moved, the inclined bracket 88 is moved with it and pickup raising pin 86 is raised to contact screw head 112 in pickup arm 99. Continued motion of the eccentric wheel forces the pin 86 against screw 112, lifting record groove following stylus out of the grooves. As the rotation of the eccentric continues still further, slide bar is moved so that the portion 91 of the slide bar 69 strikes edge of lever 92 rotating the pickup arm 5 away from the center of the record.

The rotation of pickup arm rotating lever forces lever 113 to revolve with it through the action of spring 114. This rotation is communicated through the link 164, the stud 165 sliding in the slot 166 until it reaches the end, after which the sector 167 is rotated and the lever 170 is forced against the stop pin 181, slipping the friction spring on the top of sector 167. During this time, lug 93 on the slide bar 69 contacts end 94 of 40 the ejector opening lever 95, and rotating lever 45 45 the link 155 to rotate shaft 141, ejecting a record through the action of cam 140 and ejector slide 134. At 50 this time the eccentric wheel has reached the point where the maximum radius passes between the two rotating shafts. At this instant, the slide bar ceases its inward direction and starts its outward motion. In its outward motion lug 91 on the slide bar releases lever 92 and the action 55 of the spring 114 swings the pick-up arm toward the edge of the record. Spring action continues until tab 117 contacts the side of lever 113.

It will be seen that the inward swinging of the pickup is determined by the position of lever 113 which in turn is determined by the position of the lever 120. Thus if lever 120 is moved outwardly against the action of spring 125, slide portion 118 will not contact upturned portion of lever 120, but the stop 121 of lever 113 will strike upturned portion 119 instead. Since the position of this slide lever is determined by the position of the ejector head, the pickup will come to the playing edge of either a ten inch or a twelve inch record, depending on the portion of the ejector head. The continued outward motion of the slide bar 69 causes lug 98 to contact end 94 of lever 95, rotating the cam in the ejector head to its rest 70 position and putting the ejector in position to 75

engage the edge of the next record. The continued rotation of the eccentric wheel returns it to its indexed position, and in so doing the slide 69 returns and pin 86 slides down the incline allowing record groove following stylus to rest on the surface of the record. From this point the action of the machine continues in the same cycle until all of the stacked records have been released from the supporting spindle.

It will be seen that there has been provided a simple mechanism adapted to carry out the objects of the invention, that the mechanism is simplified, economical in construction, rugged and has a minimum amount of adjustments.

After a study of the functions of the device it will be observed that there are a minimum number of adjustments. The first for positioning the stylus on the edge of the record, and the second for adjusting the height to which the pickup may be raised above the stack of records positioned on the turntable.

Having described one embodiment of this invention said description is understood to limit in no way the spirit or scope of this invention as defined in the following claims.

I claim:

1. In a record changer having a frame, a pickup arm for picking up recorded vibrations from the records and a support for carrying said pickup arm, a turntable, a turntable spindle rotatably carried by the frame, and means for supporting a stack of records above the turntable including an ejector mechanism for ejecting records from the support onto the turntable; a record ejecting actuating means therefor including a drive ring on said spindle, a member movably supported by the frame and having independent cam surfaces for engagement with said pickup arm support for raising the pickup arm and swinging the pickup arm, and a lever connected to the ejector mechanism and arranged to be operated by the member and means for moving said member comprising a rotatable cam carried by said member and adapted for engagement with said driving ring to cause said ring to rotate the cam and move said member, and means carried by said member and positioned for operative engagement with said record ejector lever to release a record onto said turntable in timed relation to the movement of the pickup arm.

2. In a record changer having a frame, a pickup arm for operation with the records and a support for carrying said pickup arm, a turntable, a turntable spindle rotatably carried by the frame and a driving ring carried by said spindle, means for supporting a stack of records above the turntable including an ejector mechanism for ejecting records from said support onto the turntable; a record ejecting actuating means comprising a member slidably supported by the frame and having independent cam surfaces for engagement with said pickup arm support for raising the pickup arm and swinging the pickup arm, and a lever connected to the ejector mechanism and arranged to be operated by the member and means carried by said member for moving said member including a rotatable cam wheel adapted to be moved into engagement with said driving ring and said ring when engaged with said cam to cause the cam to rotate and slide said member, and means carried by said slide member and positioned for operative engagement with said record ejecting means to release a record from

said support onto said turntable in timed relation to the movement of the pickup arm.

3. In a record changer of the class described having a frame, a turntable spindle rotatably carried by the frame and a turntable disposed on said spindle, a pickup arm and means for supporting said pickup arm for universal movement on said frame, said pickup arm adapted to cooperate with a record on the turntable to reproduce sounds therefrom, means for supporting a stack of records above the turntable including a center support and a side support, said side support having means for ejecting records from the stack to cause them to be discharged from the center and side support and to fall onto the turntable; operating means for said record side support and pickup arm comprising a control member movably supported on said frame and having an eccentric member mounted on said control member for moving said control member when brought into driven engagement with the spindle; said control member being connected to the pickup arm support and arranged upon movement thereof to raise the pickup arm support, a second cam means on said control member connected to the pickup arm for swinging said pickup arm to one side of the turntable and a third cam on said control member, and a lever connected to said side support and arranged to be moved by said third cam for operating said ejecting mechanism upon movement of said control member.

4. In a record changer of the class described having a frame, a hollow turntable spindle rotatably carried by the frame and a turntable carried by said spindle, a pickup arm and means for supporting the arm on said frame, said arm adapted to cooperate with a record on the turntable to reproduce sounds therefrom, means for supporting a stack of records above the turntable including a center support and a side support, said side support having an ejector for ejecting records from the stack to cause them to fall onto the turntable; operating means for said ejector and pickup arm including a control member slidably supported on said frame and carrying an eccentric wheel adapted to be moved for cyclic driven connection with said spindle; cam means on said control member connected to the pickup arm support for raising the pickup arm on movement of the control member, a second cam means thereon connected to the pickup arm support arranged to swing said pickup arm to one side of the turntable on movement of the control member, a lever connected to said ejector, a third cam means thereon arranged to contact said lever for operating said ejecting mechanism on movement of the control member, and means connected to the pickup arm and operable by the pickup arm to move said control member and said eccentric wheel into connection with the rotatable spindle to initiate the cyclic operation of said eccentric wheel.

5. In an automatic record changer of the class described having a turntable and a drive spindle therefor, a pickup arm, means for supporting a stack of records above the turntable including a stationary spindle for supporting the records at their centers and a side support for supporting them adjacent their edges, said support for the edges being disposed spaced from the turntable and containing an ejecting mechanism for ejecting the records from the side support and stationary spindle; means connected to the pickup

arm and the side support for effecting the ejection of the records comprising a slide bar slidably supported below the turntable and a wheel eccentrically mounted thereon adjacent the turntable spindle, said slide member adapted to support said wheel in normally spaced relation from said spindle, means connected to the pickup arm and operable by the pickup arm to move said eccentric wheel into driving engagement with said spindle, and means carried by the slide bar and connected to the pickup arm and controlled by said slide bar to raise the pickup arm and a second means controlled by the slide bar to swing the pickup arm beyond the edge of the turntable; a linkage connected to said ejector and slide bar and operable by said slide bar to operate said ejector to eject a record from the stack onto the turntable in timed relation to the movement of the pickup arm.

6. In a mechanism of the class described having a frame, a turntable rotatably carried by the frame on a spindle, a pickup arm for reproducing records on the turntable, means for supporting records above the turntable and including means for placing records on the turntable in playing position; means for raising, swinging, and lowering the pickup arm in timed relation to the deposition of records on the turntable comprising a member slidably supported below the turntable, means driven by said turntable spindle for moving said member cyclicly, means for supporting said pickup arm including a rotatable member connected to the arm and extending downward through the frame and near the slide member, a lever rotatably supported by said rotatable member and a second lever carried and held against relative rotatable movement by said rotatable member and spring means connecting said levers, said slide member having a projection for engagement with the second lever to rotate the same, said rotational movement being communicated to the rotatable lever through said spring.

7. In a mechanism of the class described having a frame, a turntable rotatably carried by the frame, a pickup arm for reproducing records on the turntable, means for supporting records above the turntable and including means for placing records on the turntable in playing position; means for raising, swinging, and lowering the pickup arm in timed relation to the deposition of records on the turntable including a member slidably supported below the turntable on said frame, means for moving said member cyclicly, means for supporting said pickup arm and arranged to swing the arm including a rotatable member connected to the arm and extending through the frame and adjacent the slide member, a first lever rotatably supported by said rotatable member and a second lever carried and held against relative rotatable movement by said rotatable member and spring means connecting said levers, said slide member having a projection for engagement with the second lever to rotate the same, said rotational movement being communicated to the first rotatable lever through said spring, and means disposed in the path of the first rotatable lever to limit the movement thereof, said other second lever adapted to be moved by said slide member and to swing said pickup arm beyond the confines of the turntable and upon being released by the slide member, said spring means adapted to swing said second lever and said pickup arm back toward

the first rotatable lever, and means on the second lever adapted upon contact with the first rotatable lever to terminate the swinging movement and to index the position of the pickup arm for the start of the playing of a record.

- 5 8. In a mechanism of the class described having a frame, a turntable rotatably carried by the frame, a pickup arm for reproducing records on the turntable, means for supporting records above the turntable and including means for placing records on the turntable in playing position; means for raising, swinging, and lowering the pickup arm in timed relation to the deposition of records on the turntable comprising a member slidably supported below the turntable, means for moving said member cyclicly to cause the slide member to effect the record changing function, means for supporting said pickup arm and arranged to swing the arm including a rotatable sleeve connected to the arm and extending downward through the frame and near the slide member, a first lever rotatably supported by said rotatable sleeve and a second lever carried and held against relative rotatable movement by said rotatable sleeve and spring means connecting said levers, said slide member having a projection for engagement with the second lever to rotate the same, said rotational movement being communicated to the first rotatable lever through said spring, and means disposed in the path of the first rotatable lever to limit the movement thereof, said second lever adapted to be contacted by said slide member and to be moved by said slide member and to swing said pickup arm beyond the confines of the turntable and said second lever upon being released by the slide member said spring means adapted to swing said lever and said pickup arm back toward the first rotatable lever, and means on the second lever adapted upon contact with the first rotatable lever to terminate the swinging movement and to index the position of the pickup arm for the start of the playing of a record, said stop means for the first rotatable lever being adjustable to stop the lever in different positions to index the pickup arm for ten inch or twelve inch records.

- 10 45 9. In an apparatus of the class described, having a rotatable spindle and a turntable thereon, a pickup arm for reproducing records rotated by the turntable, means for supporting records in position to be deposited on the turntable; means for moving the pickup arm in properly timed relation to the deposition of the records and for causing the deposition of said records comprising a member slidably supported below the turntable and having an eccentric wheel carried thereby adapted for driven engagement with said spindle, said wheel being normally out of engagement with said spindle, a cam member carried by said eccentric wheel and a spring connected to the movable member for moving the eccentric wheel into engagement with said spindle, a pawl supported by the slide member and engageable with the cam to hold the cam against movement by the spring, a linkage connected to said pickup arm and movable by the pickup arm to release said pawl from locking engagement with said cam to cause said eccentric wheel to be moved into engagement with said spindle.

- 15 50 55 60 65 70 75 10. In an apparatus of the class described, having a rotatable spindle and a turntable thereon, a pickup arm for reproducing records rotated by the turntable, means for supporting records in

position to be deposited on the turntable; means for moving the pickup arm in properly timed relation to the deposition of the records and for causing the deposition of said records comprising a member movably supported below the turntable and having an eccentric wheel carried thereby adapted for driven engagement with said spindle, said wheel being normally out of engagement with said spindle, a cam member connected to said eccentric wheel and a spring connected to the cam and the movable member for moving said cam and the eccentric wheel into engagement with said spindle, a pawl supported by the movable member and engageable with the cam to hold the cam against movement by the spring, said spindle having a lug extending therefrom and rotatable therewith, a linkage controlled by the pickup arm to be moved into the path of the lug on said spindle and said lug on said spindle adapted to engage said linkage and move said linkage into engagement with said pawl to move said pawl to cause said cam to be released from its indexed position and to urge said eccentric wheel into driving engagement with said spindle.

11. In an apparatus of the class described having a supporting frame, a turntable and means to rotate the same, a pickup arm for playing records on said turntable, means for supporting a stack of records above said turntable including a stationary member for holding the records at their centers and a second member for supporting the records at their edges, said side support having means for engaging the edge of the bottom record of the stack to dislodge the record from the center and side supports and the center support having guiding means for guiding records onto said turntable, a support for said pickup arm and a push rod for raising and lowering the pickup arm and a sleeve connected to said arm for swinging said arm; means for moving the pickup arm and operating the ejector means in properly timed relation for changing a

record comprising a lever fixedly secured to said sleeve and a second lever rotatably disposed on said sleeve adjacent said first lever, one of said levers having a lug for engagement with the other lever to limit their relative movement in one direction, and a spring connecting said levers to each other, one of said levers adapted to be moved by the sleeve and the other by reason of said spring connection, means for effecting the movements of the pickup arm and ejector mechanism in proper timed relation to effect the playing and changing of the record including a slideable member supported by the frame below the turntable and having a cam for cooperation with said push rod to raise and lower the pickup arm upon longitudinal movement of said slide, a second cam on said slide engageable with said first lever to move the lever in one direction only and index means connected to and controlled by said record support to limit the movement of the second lever, said second lever adapted to be stopped by said index means and said first lever adapted to be swung by said slide against the tension of said spring to swing the pickup arm beyond the edge of the turntable, said slide having a third cam and said ejector having a linkage connected thereto and extending for cooperation with said third cam to eject a record from said supports when the pickup arm is moving beyond the edge of the turntable and said spring adapted to return said pickup arm to indexed position determined by said second lever when said first lever is released by said slide, and means connected to said second lever and operable by the pickup arm in the run-out groove of the record to move said eccentric wheel from its normally disengaged position into engagement with driving means for said wheel to cause said wheel to rotate one complete revolution and to move said slide longitudinally during said revolution.

WILLARD J. FAULKNER.

CERTIFICATE OF CORRECTION.

Patent No. 2,331,383.

October 12, 1943.

WILLARD J. FAULKNER.

It is hereby certified that error appears in the printed specification of the above numbered patent requiring correction as follows: Page 2, second column, line 47, for the word "its" read --it--; page 3, first column, line 63, for "being" read --becoming--; page 7, second column, line 64, for "slide" read --side--; page 8, first column, line 62, claim 2, after "surfaces" insert --thereon connected to the pickup arm--; and that the said Letters Patent should be read with this correction therein that the same may conform to the record of the case in the Patent Office.

Signed and sealed this 21st day of December, A. D. 1943.

Henry Van Arsdale,

(Seal)

Acting Commissioner of Patents.
